PORTABLE LIQUID DISPENSER CASING

Elliot F. Dolgin, San Francisco, Calif., assignor to Fen-Mart, Inc., Reno, Nev., a corporation of Nevada

Filed Dec. 29, 1960, Ser. No. 63,392

Term of patent 14 years

(Cl. D2—3)

Fig. 1.

Fig. 2.

Fig. 3.

Fig. 4.

Fig. 5.

FIG. 1 is a rear perspective view of a portable liquid dispenser casing, showing my new design and illustrating the top, rear and one side thereof;

FIG. 2 is a top plan view thereof;

FIG. 3 is a side elevation thereof;

FIG. 4 is a bottom plan view thereof; and

FIG. 5 is a front perspective view thereof taken diametrically opposite from FIG. 1.

The broken line showing of a jug and connections therefor in FIG. 4 are included for illustrative purposes only.

I claim:

The ornamental design for a portable liquid dispenser casing, as shown and described.
